DESIGN FOR A FILM CLIP

Carter J. Hughey, Rochester, N. Y., assignor to Eastman Kodak Company, Rochester, N. Y., a corporation of New Jersey

Application September 23, 1941, Serial No. 103,457

Term of patent 14 years

To all whom it may concern:

Be it known that I, Carter J. Hughey, a citizen of the United States, residing in Rochester, in the county of Monroe and State of New York, have invented a new, original, and ornamental Design for Film Clips, of which the following is a specification, reference being had to the accompanying drawing, forming a part thereof.

In the drawing:

Fig. 1 is a side elevation of the film clip showing my new design;

Fig. 2 is a bottom plan view of the film clip shown in Fig. 1;

Fig. 3 is a top plan view of the film clip shown in the preceding figures.

I claim:

The ornamental design for a film clip, as shown.

CARTER J. HUGHEY.
